(57) **CLAIM**

The ornamental design for the microbial house for wastewater purification system as shown and described.

DESCRIPTION

FIG. 1 is a front isometric view of a microbial house for wastewater purification system showing my new design, the rear isometric view being identical thereto;

FIG. 2 is a front elevation view of the microbial house for wastewater purification system of FIG. 1, the rear elevation view being identical thereto;

FIG. 3 is a left side elevation view of the microbial house for wastewater purification system of FIG. 1, the right side elevation view being identical thereto;

FIG. 4 is a top, plan view of the microbial house for wastewater purification system of FIG. 1, the bottom plan view being identical thereto;

FIG. 5 is a cross-sectional view of the microbial house for wastewater purification system, taken substantially along lines 5-5 of FIG. 2;

1 Claim, 4 Drawing Sheets
